(57) **CLAIM**

I claim the ornamental design for a pairable protective case, as shown and described.

DESCRIPTION

FIG. 1 is a perspective view of a pairable protective case, showing my new design;

FIG. 2 is a front elevation view thereof;

FIG. 3 is a rear elevation view thereof;

FIG. 4 is a top plan view thereof;

FIG. 5 is a bottom plan view thereof;

FIG. 6 is a left-side elevation view thereof; and,

FIG. 7 is a right side elevation view thereof.

The broken lines indicate unclaimed portions of the article that form no part of the claimed design.
